Fig. 5

Fig. 1 is a view in front elevation of a cabinet handle, embodying our new design.

Fig. 2 is a view in side elevation of our cabinet handle.

Fig. 3 is a bottom plan view of our cabinet handle,

Fig. 4 is a top plan view of our cabinet handle, and

Fig. 5 is a perspective view of our cabinet handle design.

The novel features of this design reside in the full line portions of the drawing. The dotted lines in Figs. 2, 3, and 4 show portions of the rear surface of our cabinet handle and positioning lugs which are not visible when the handle is installed on a cabinet.

We claim:

The ornamental design for a cabinet handle, substantially as shown and described.
